UNITED STATES PATENT OFFICE.

WALTER L. POWER, OF SPRINGFIELD, MASSACHUSETTS; JOHN J. MURRAY, OF SPRINGFIELD, MASSACHUSETTS, ADMINISTRATOR OF SAID POWER, DECEASED.

ERECTING-STAGING.

1,134,061.

Specification of Letters Patent. Patented Mar. 30, 1915.

Application filed October 30, 1912. Serial No. 728,741.

To all whom it may concern:

Be it known that I, WALTER L. POWER, a citizen of the United States of America, residing at Springfield, in the county of 5 Hampden and State of Massachusetts, have invented new and useful Improvements in Erecting-Staging, of which the following is a specification.

This invention relates to an erecting staging of improved construction.

The invention has been found particularly useful in erecting the elevator shafts in high buildings but is broadly capable of analogous uses. In erecting elevator shafts 15 it is necessary to use and support heavy erecting tools and since the fittings are for the most part on the side walls of the shaft extending continuously from bottom to top the work of erecting occurs adjacent the 20 walls. It is, therefore, desirable to provide a working platform adapted to give a free working space at the working points and at the same time support heavy loads at such points without tipping the platform. 25 It is also desirable to provide for all vertical adjustments of the platform so that the workmen can operate at the most convenient levels.

The object of this invention is to provide 30 an erecting staging with the desired advantages named which will be simple of construction and economical to put up and use.

The invention can be embodied in various forms and I have chosen only one form 35 which shows the preferred embodiment of my invention for purposes of illustration.

This form is shown in the accompanying drawings in which,—Figure 1 is a vertical section of an elevator shaft in process of 40 construction showing the erecting staging in its relation thereto. Fig. 2 is a horizontal section of the same showing the staging in plan view.

In the drawings *a* represents the walls or 45 frame work of the elevator shaft, which, as far as this invention is concerned, may be in skeleton form or inclosed as shown. The several floors are represented by *r* and *q*. The staging comprises a lower frame *o* made 50 of four pieces of planking made into a square and a working platform *p* above *o* and connected thereto by the rigid pipe members *m*, one fastened firmly to each corner of *o* at one end, and at the other end to 55 platform *p*, but away from the corners and

edges of *p*. The platform *p* is of larger area than frame *o*, there being around the edges of platform *p*, outside of the square formed by the four points of attachment of members *m*, a free working space unobstructed by any of the constructional details of the staging. This platform is arranged to hold working tools *h* and *i*.

It can be seen that the frame piece *o* and platform *p* together with rigid connecting members *m* form a very firmly constructed staging capable of withstanding severe strains when properly supported. In order to support this staging the chains *e* are attached to the four corners of the frame *o* 60 and brought together by attaching them to tackle *f*, the ropes *g* of which can be operated to give any desired vertical adjustment of the staging. Four vertical tightly strung wires *c* pass through frame *o*, platform *p* 65 and connecting members *m*. These wires serve not only as guide wires but as binding means against which the rigid connecting members *m* bear whenever there is the least tendency for the platform to tip or tilt. 70 The members *m* have an effective length to bind against wires *c*, and since the latter are tightly strung they take the strain caused by heavy loads on the working space 75 at the edge of the platform. Thus the wires 80 aid in supporting the platform and positively prevent any tilting thereof. Furthermore the staging can be raised and lowered on the wires without the least inconvenience. Wires have before been used for 85 guiding platforms, for instance, in dumb-waiter constructions, but, as far as known, this construction has not been used to provide a guiding and supporting means in combination with a working platform 90 designed to cause a binding action on the 95 wires.

The free working space, as at edges *k* and *l*, affords easy access to the sides of the shaft and in the position shown are adapted 100 for erecting the elevator guides. It is clear that with workmen standing on the working spaces they are unhampered by the supporting means for the platform and, at the same time, the supporting and guiding 105 means positively prevent any tipping of the platform.

What I claim, is:—

An erecting staging, comprising, in combination, a series of guiding cables, a rigid 110

upper working platform, a rigid lower horizontal frame, vertically arranged means rigidly holding said platform and frame in spaced relation, said means being connected 5 to the underside of the platform well within the periphery thereof, said vertically arranged means, platform, and frame being constructed and arranged to receive and embrace said series of tightly strung guide cables, each passable through said platform well within the periphery thereof, whereby 10

the platform is left with a free working space around its periphery and is prevented from tipping due to weight on or adjacent the periphery and adjustable supporting 15 means for the platform spacing means and frame.

WALTER L. POWER.
